United States Patent Office

Des. 204,338
Patented Apr. 5, 1966

204,338

ELECTRIC ENVELOPE OPENER

William B. MacKrell, Mendota Heights, Minn., assignor
to Standard Packaging Corporation, New York, N.Y.,
a corporation of Virginia

Filed Oct. 5, 1964, Ser. No. 82,028

Term of patent 3½ years

(Cl. D74—10)

FIG. 1

FIG. 2

FIG. 3

FIG. 4

FIG. 5

FIG. 6

FIGURE 1 is a perspective view of an electric envelope opener showing my new design; and

FIGURE 2 is a front view thereof; and

FIGURE 3 is a top plan view thereof; and

FIGURE 4 is a view of the right end of the opener with reference to FIGURE 3; and

FIGURE 5 is a view of the left end of the opener with reference to FIGURE 3; and

FIGURE 6 is a rear view of the opener.

I claim:

The ornamental design for an electric envelope opener, as shown.
